MEANS FOR SUPPLYING HEATED AIR TO
THE ROOMS OF A BUILDING

Henry James Newlin, Birmingham, England

Application May 3, 1938, Serial No. 205,855

5 Claims. (Cl. 126—121)

This invention relates to means for supplying heated air to the rooms of a building of the type in which the air is heated by flowing through a passage incorporated in a fire place.

With fire places as at present constructed a large proportion of the heat escapes up the chimney, and this invention has for its object to absorb the heat which normally escapes up the chimney, to heat air which is directed into a room or rooms of a building to heat such rooms and recondition the air in such rooms. By this invention it is possible to utilise an open fire located in one room to heat other rooms in the building. By this invention also an improved construction of fire place is obtained, as well as an improved arrangement of supporting the fire unit.

In order that the invention may be clearly understood and readily carried into effect, reference may be had to the accompanying drawings on which:

Figure 1 is a cross-sectional elevation of an air heating device and room warming device constructed according to this invention, the section being taken on line I—I of Figure 2.

Figure 2 is cross-sectional elevation, the section being taken on line II—II of Figure 1, and

Figure 3 is a sectional plan, the section being taken on line III—III of Figure 1.

Figure 4 is a section of the upper portion of the chimney shown in Figure 2, the section being in the same plane.

Figure 5 is a section on line V—V of Figure 4.

Figure 6 plan view of the fire grate, and

Figure 7 is a plan view of a room of the building.

According to a convenient embodiment of this invention, the fire-place is arranged to form an open fire in the interior wall 1 of a room in the building, for instance a ground floor room, the fire-place opening having a tiled surrounding wall 2. The fire-place 3 is constructed as a self-contained expandible and contractable unit, comprising the fire-well 4 and walls 5 of the fire-box leading the products of combustion to the chimney 6. This self-contained unit also includes the air passages 7 on each side of the fire-box, the walls of such passages being continued below the fire-well and shaped to open into a fresh air inlet passage 8 under the floor of the building. The fire may be automatically fed by the gravity chute 9. An ash-pit 10 is fixed under the fire-grate and has inclined walls for delivering the ashes to the rear of the fire-place. The wall of the fire-box is also fitted with water boilers 11.

All the parts thus constructed are built up as a single structure and the front and rear walls have supporting rails 12 fixed thereto which are slidably engaged on the beams 13 in the walls 14 surrounding the fire-place and the chimney. The fire-place unit 3 is thus suspended as a whole and is free to expand and contract. An air seal is also obtained and for this purpose, in addition to the rails 12, side angle-bars 14a and 15 are fixed to the unit, the bar 14a conveniently engaging a groove in the wall whilst the bar 15 is fixed to a girder 16. A removable cover 17 is fixed over the opening in the wall through which the fire-place unit is passed, and this cover may be afterwards bricked over.

The fire-place unit is enclosed by brick walls 1, 14 and 18 which are carried to the top of the building. The chimney 6 is fixed to the top of the fire-box, and this chimney is formed of metal in order to conduct the heat of the gases passing up the flue to the air to be warmed. A larger metal or other tube 19 surrounds the chimney 6 and is fixed to the top of the unit 3, the base of the tube 19 being shaped, so that the passages 7 merge therein.

The air to be heated is drawn up the passages 7 and the annular passage 20 by a fan 24 which delivers the hot air to the rooms to be heated. The fan is conveniently located in a chamber 21 in the roof of the building, which communicates with the annular passage 20 by the opening 21a, the top of the passage 20 being closed by the plate 22. The hot air is conveniently delivered by the fan into the spaces 23 between the walls 1, 14 and 18 and the tube 19. The fan 24 delivers the air into the passage 25 and through the opening 25a and the top of the spaces 23 are closed by the plate 26. The fan can also draw in fresh air from the atmosphere, or partly from the annular passage 20 and partly from the atmosphere. For this purpose a valve plate 27 is pivoted at 28 and is adapted in one position to close the opening 21 and in another position to close the aperture 29 open to the atmosphere. In intermediate positions air through both openings is drawn in by the fan. The temperature of air supplied to the rooms of the building can thus be regulated. The valve 27 may be thermostatically controlled.

The opening 29 in the roof is closed by a hood 30 the front of which is closed by louvres 31. The air delivered by the fan into spaces 23 is conducted into the required room or rooms in the building by means of any suitable passage or conduit, for instance, the air may pass through the space or conduit 32 under the floor and 33

into the room through a grating or opening 33 in a floor 34. The opening 33 may be conveniently located near the top of a room. The outlet for the air in this room is conveniently provided in 5 a wall near the floor of the room, this wall being, conveniently a hollow wall which will allow the air to pass up the wall and out into the roof space. By so arranging the flow of air the fabric of the building is heated and very little heat 10 escapes into the atmosphere. The warm air delivered by the fan 24 can however be delivered into any desired arrangement or construction of distributor conduit. In the construction illustrated, the walls enclosing the chimney also 15 form the walls of a distributor conduit, and the air passing therethrough is further heated.

The warm air delivered by the fan 24 may also be utilized for obtaining a forced draught for the fire, and for this purpose the space 35 under 20 the grate is enclosed and is connected by the conduit 36 to the passage 23, a damper being provided to control this forced draft.

In order to increase the draft up the chimney a pipe may be connected to the delivery side of 25 the fan 24.

The chimney is supported at the upper end to permit of expansion and contraction and to seal the joint, and for this purpose an annular vessel 38 is connected by a flange 39 to the brick walls 30 18 whilst the chimney carries a flange 49 having the depending ring 40 which dips into water in the vessel 38. The wall of the vessel carries spring tongues 41 which bear against the chimney and support the same in a central position. 35 Water may be continuously fed to the vessel 38 through the conduit 42, the flow through the conduit being controlled by the needle valve 43. An overflow aperture 38a is provided in the vessel 38 so that water can overflow and humidify 40 the air passing through fan 24.

The grate 4a at the bottom of the fire-well is constructed to form fire bars 44 which lie over the ash-pit 10 and with perforations 45 which lie over the enclosed space 35 through 45 which forced draft passes.

The forced draft therefore does not flow through the ash-pit and ashes are not liable to be blown out through the chimney.

The fire-box aforescribed is constructed 50 without the use of firebrick, as the walls are cooled by the air passages and the water boilers. The damper 44a controlling the conduit 36 may be connected to the thermostatically controlled valve 27 by means of the wire or rod 45a which 55 is connected to the damper and to an arm 46 on the valve. The forced draught will therefore be reduced when less heat is required to be supplied to the room or rooms. In lieu of drawing the air up the passages 7 and 20, the 60 air to be heated may be caused to flow down such passages. For instance if the fan 23 is reversed air will be drawn in through a conduit such as 32 which may open to the outside atmosphere and the heated air is passed to the 65 passages 8, to which may be connected distributing conduits for supplying air to the rooms. In the example illustrated the conduit 32 may also deliver air to a grating in the ceiling of an under room.

70 I claim:

1. Means for supplying the rooms of a building with heated air, having a fire-place comprising an expansible and contractable unit forming a fire-well and walls for the fire-well leading the products of combustion to the chimney.

means for suspending the unit so that it is free to expand downwardly, a chimney of heat conducting material fixed to the fire-place unit, air passages around the fire-well and forming part of the fire-place unit and a tube fixed to the 5 said fire-place unit and forming an air passage leading from said passages and surrounding the said chimney.

2. Means for supplying the rooms of a building with heated air, having a fire-place comprising an expansible and contractable unit forming a fire-well and walls for the fire-well leading the products of combustion to the chimney, means for suspending the fire-place unit in sealed contact with the structure of the building and 10 so that it is free to expand downwardly, comprising flanges or ledges on the front and rear of the fire-place unit which bed on ledges of the building structure, a chimney of heat conducting material fixed to the said fire-place unit, air 15 passages around the fire-well and forming part of the fire-place unit and a tube fixed to said fire-place unit and forming an air passage leading from said passages and surrounding the said chimney. 20

3. Means for supplying the rooms of a building with heated air, having a fire-place comprising an expansible and contractable unit forming a fire-well and walls for the fire-well leading the products of combustion to the chimney, an ash 30 pit under the fire-well and air passages on the outside of the fire-box forming part of the said fire-place unit, means for suspending the said unit so that it is free to expand downwardly, a 35 chimney of heat conducting material fixed to the said fire-place unit, air passages around the fire-well and forming part of the fire-place unit and a tube fixed to said fire-place unit and forming an air passage leading from such passages and surrounding the chimney. 40

4. Means for supplying the rooms of a building with heated air, having a fire-place unit comprising a fire-box formed of a fire-well and walls for the fire-well leading the products of combustion to the chimney, an ash-pit under the 45 fire-well and forming part of the said unit, air passages on each side of the fire-well and forming extensions thereof, flanges on the sides of the fire-place unit for suspending such unit from the building structure, a metal chimney supported by the fire-box and an outer tube surrounding the chimney supported by the fire-place unit and forming a chamber with which the said air 50 passages of the fire-place unit communicate. 55

5. Means for supplying the rooms of a building with heated air, having a fire-place unit comprising a fire-box formed of a fire-well and walls for the fire-well leading the products of combustion to the chimney, an ash-pit under the fire-well, forming part of said unit, air 60 passages on each side of the fire-well and forming extensions thereof, flanges on the front and rear walls of the fire-place unit freely resting on ledges of the building structure, means for fixing one side of the said unit to the building structure and a projecting rib on the other side for freely engaging the building structure to suspend the unit in sealed relationship with the building structure, a metal chimney supported by the fire-box and an outer tube surrounding 65 the chimney supported by the fire-place unit and forming a chamber with which the said air 70 passages of the fire-place unit communicate.
